UNITED STATES PATENT OFFICE.

GEORGE HUGHES, OF CANTON, OHIO.

METALLIC STRUCTURAL ELEMENT FOR BUILDINGS.

Application filed November 10, 1925. Serial No. 68,142.

This invention as indicated, relates to metallic structures, and more particularly to metallic door and window sash construction.

Among the objects of the invention are the provision of a strong yet light construction which is adaptable for use in various relations, and the provision of a simple and effective manner of connecting the elements of the structure.

Other objects and advantages will appear as the description proceeds.

To the accomplishment of the foregoing and related ends, the invention then, consists of the means hereinafter fully described and particularly pointed out in the claim, the annexed drawing and the following description setting forth but one of the various ways in which the principle of the invention may be used.

In said annexed drawing:—

Fig. 1 is an elevation of a door construction in accordance with my invention; Fig. 2 is a transverse section of the stile, the section being taken on the plane indicated by the line II—II, Fig. 1; Fig. 3 is a transverse section of the bottom rail, the section being taken on the plane indicated by the line III—III, Fig. 1; Fig. 4 is a transverse section of a blank in course of formation into a stile; Fig. 5 is a transverse section showing a further stage; and Fig. 6 is an isometric view of the key element.

In the form of the invention illustrated, a blank of suitable sheet metal is shaped, ordinarily for instance sheet steel, with beading or as desired, into a general longitudinal bevel offset at 2 and is longitudinally flanged as at 3 and again at 4 (Fig. 4). The side wings 5, 6 are now bent in or folded along longitudinal right angle folds at 7 so as to present spaced parallel lateral walls 5', 6', and allow the margins to converge generally bevelwise, with the flanges interiorly and directed parallel and then outwardly, as in Fig. 5. In this manner, framing elements, as stiles and rails, may be formed as required. The panel can be of two sheets spaced apart throughout but united at the edges, or of one sheet flanged over or thickened at the edges to fit the recess between the flanges of the stile, etc. To lock the parts together, key elements 11 are driven in longitudinally along the flanges 3, a central abutment 12 of the key acting as a support to the flanges and engaging the edge generally of the panel, the key having suitable resiliency

and firmness to bind the flanges against the panel, the key for each rail or stile being placed in its position as these respective elements are successively assembled. The bottom rail has an opening in its lower edge through which the key for the last-assembled stile can be inserted.

In assembling, the preferable procedure is to bring the top rail and the panel together, with the edge of the panel between the flanges of the rail, and a key is then driven in along and embracing the flanges. A stile is then similarly placed with an edge of the panel between the flanges of the stile and a key is driven along the flanges; similarly the bottom rail and other stile are brought into position and fastened with the panel. The key for the last stile is inserted through the opening in the lower edge of the bottom rail, the opening being then closed, if desired, by a closure element 14, which is secured, for instance by welding or soldering.

It will be understood that the panel member can be of metal, wood or glass, and that while I have referred more particularly to a door in the foregoing, my construction may be used in doors, windows, or partitions, etc.

Other modes of applying the principle of my invention may be employed instead of the one explained, change being made as regards the details disclosed, provided the features stated by the following claim, or the equivalent of such, be employed.

I therefore particularly point out and distinctly claim as my invention:—

In a metallic structure of the character described, the combination of stiles and upper and lower rails having spaced parallel lateral walls and interior flanges, said flanges having spaced straight parallel walls and laterally-turned edges, a panel member engaged at its margins between the parallel walls of said flanges, and keys embracing said flanges, said keys having a central abutment with parallel walls to engage the parallel walls of said flanges and having lateral resilient margins to bear against the outside faces of the parallel walls of the flanges angularly, said lower rail having an opening in its lower edge for admission of the stile key.

Signed by me this 7th day of November, 1925.

GEORGE HUGHES.
